US00D971413S

(12) **United States Design Patent** (10) Patent No.: **US D971,413 S**
(45) Date of Patent: **** Nov. 29, 2022**

(54) **HEARING AID**

(71) Applicant: **Sonova AG**, Stäfa (CH)

(72) Inventor: **Rafael Tamsiran**, Amersfoort (NL)

(73) Assignee: **Sonova AG**, Staefa (CH)

(**) Term: **15 Years**

(21) Appl. No.: **35/511,545**

(22) Filed: **Feb. 2, 2021**

(80) **Hague Agreement Data**

Int. Filing Date: **Feb. 2, 2021**

Int. Reg. No.: **DM/213102**

Int. Reg. Date: **Feb. 2, 2021**

Int. Reg. Pub. Date: **Mar. 19, 2021**

(51) **LOC (13) Cl. 24-99**

(52) **U.S. Cl.**

USPC **D24/174**

(58) **Field of Classification Search**

USPC D14/188, 192, 205, 206, 223; D24/105, D24/106, 173, 174; D28/9, 99

CPC A61F 11/00; A61F 11/08; A61F 11/10; A61F 11/085

See application file for complete search history.
